Attorney

UNITED STATES PATENT OFFICE.

HAROLD M. TENNANT, OF SAN JOSE, CALIFORNIA.

COMFORT GRIP.

Application filed September 13, 1922. Serial No. 588,099.

To all whom it may concern:

Be it known that HAROLD M. TENNANT, a citizen of the United States of America, residing at San Jose, in the county of 5 Santa Clara and State of California, has invented new and useful Improvements in Comfort Grips, of which the following is a specification.

The object of the invention is to provide 10 simple and efficient means for holding lap robes, steamer rugs, bed clothing and the like in proper position without necessitating the constant use of the hands to avoid displacement due to jarring, wind, or the like; 15 and with this object in view the invention consists in a construction and combination of parts of which a preferred embodiment is shown in the accompanying drawings, wherein:—

20 Figure 1 is a perspective view, and Figure 2 is a plan view of a holder or grip embodying the invention.

Figure 3 is a side view indicating in dotted lines the arrangement of the robe or 25 comfort in relation thereto.

The device consists of a transversely arched or looped frame 10 carrying cooperative jaws 11 and 12 of which the latter is rigidly attached to one end of the frame by 30 the screws 13 or the equivalent thereof while the former is pivotally mounted upon the other end of the frame by means of a screw 14 or its equivalent, anchoring means being adapted for connection with the second-named jaw through the agency of an eye 15 and a flexible connection 16 consisting of a tape or the equivalent thereof which may be tied to the side of a vehicle seat or a steamer chair or a bedstead.

40 Carried by and arranged in operative relation with the fixed or stationary jaw 12 of the device is a bowed spring 17 terminally attached in the construction illustrated at 18 to one side surface of said jaw and 45 terminally bearing at its free end upon the opposite side surface of said jaw, so that the edge of the robe or comfort indicated at 19 may be engaged between said free terminal of the bowed spring and the side of

the jaw 12 and thence passed between the 50 obliquely disposed cooperative faces 20 of the jaws, so that tensile strain applied to the robe or comfort engaged as indicated will tend to close the jaws and thereby increase the gripping action thereof so that 55 the possibility of disengagement is minimized. The arched portion 10^a of the frame is designed to accommodate the edge or rolled or slack portion of the robe or comfort in passing between the engaging 60 faces of the jaws, so that the jaws may engage the fabric of the robe at a sufficient distance from the edge thereof to prevent unnecessarily straining or risking the tearing thereof.

Having described the invention, what is claimed as new and useful is:—

1. A grip for the purpose indicated having cooperating clamping jaws arranged for terminal cooperative relation, one of said 70 jaws being pivotally mounted for swinging movement in the plane of the other, and a flexible anchoring connection terminally connected to the remote end of the pivoted jaw and tending under stress to keep the 75 jaws in engaged relation.

2. A grip for the purpose indicated having cooperating clamping jaws arranged for terminal cooperative relation, one of said 80 jaws being pivotally mounted for swinging movement in the plane of the other jaw, and a bowed spring carried by one of said jaws and having a free terminal yieldingly impelled toward a side surface thereof for engaging an interposed robe.

3. A grip for the purpose indicated having cooperating clamping jaws arranged for terminal cooperative relation, one of said 85 jaws being pivotally mounted for swinging movement in the plane of the other jaw, said jaws being carried by a supporting frame having a laterally bowed portion in the transverse plane of the meeting faces of the jaws.

In testimony whereof he affixes his signature. 95

HAROLD M. TENNANT.
